(57) **CLAIM**

The ornamental design for a storage basket rack, as shown and described.

DESCRIPTION

FIG. 1 is a front elevational view of a storage basket rack showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a second perspective view thereof;

FIG. 9 is a front elevational view of an alternate configuration where the storage basket rack are stacked and the trolley frame is omitted for the purpose of clearer illustration; and,

FIG. 10 is a perspective view of FIG. 9.
